CLAIM

The ornamental design for a set of modeling blocks, as shown and described.

DESCRIPTION

FIG. 1 is a front orthogonal view of a set of modeling blocks showing the new design in a first configuration;

FIG. 2 is a front view of the invention illustrated in FIG. 1 in the first configuration;

FIG. 3 is a rear view of the invention illustrated in FIG. 1 in the first configuration;

FIG. 4 is a right side view of the invention illustrated in FIG. 1 in the first configuration;

FIG. 5 is a left side view of the invention illustrated in FIG. 1 in the first configuration;

FIG. 6 is a top view of the invention illustrated in FIG. 1 in the first configuration;

FIG. 7 is a bottom view of the invention illustrated in FIG. 1 in the first configuration;

FIG. 8 is another orthogonal view of the invention illustrated in FIG. 1 in the first configuration;

FIG. 9 is an orthogonal view of the set of modeling blocks illustrated in FIG. 1 in a second configuration;

FIG. 10 is a front view of the invention illustrated in FIG. 1 in the second configuration;

FIG. 11 is a rear view of the invention illustrated in FIG. 1 in the second configuration;

FIG. 12 is a right side view of the invention illustrated in FIG. 1 in the second configuration;

FIG. 13 is a left side view of the invention illustrated in FIG. 1 in the second configuration;

(Continued)

FIG. 14 is a top view of the invention illustrated in FIG. 1 in the second configuration;

FIG. 15 is a bottom view of the invention illustrated in FIG. 1 in the second configuration;

FIG. 16 is another orthogonal view of the invention illustrated in FIG. 1 in the second configuration;

FIG. 17 is an orthogonal view of the set of modeling blocks illustrated in FIG. 1 in a third configuration;

FIG. 18 is a front view of the invention illustrated in FIG. 1 in the third configuration;

FIG. 19 is a rear view of the invention illustrated in FIG. 1 in the third configuration;

FIG. 20 is a right side view of the invention illustrated in FIG. 1 in the third configuration;

FIG. 21 is a left side view of the invention illustrated in FIG. 1 in the third configuration;

FIG. 22 is a top view of the invention illustrated in FIG. 1 in the third configuration;

FIG. 23 is a bottom view of the invention illustrated in FIG. 1 in the third configuration;

FIG. 24 is another orthogonal view of the invention illustrated in FIG. 1 in the third configuration;

FIG. 25 is an orthogonal view of the set of modeling blocks illustrated in FIG. 1 in a fourth configuration;

FIG. 26 is a front view of the invention illustrated in FIG. 1 in the fourth configuration;

FIG. 27 is a rear view of the invention illustrated in FIG. 1 in the fourth configuration;

FIG. 28 is a right side view of the invention illustrated in FIG. 1 in the fourth configuration;

FIG. 29 is a left side view of the invention illustrated in FIG. 1 in the fourth configuration;

FIG. 30 is a top view of the invention illustrated in FIG. 1 in the fourth configuration;

FIG. 31 is a bottom view of the invention illustrated in FIG. 1 in the fourth configuration; and,

FIG. 32 is another orthogonal view of the invention illustrated in FIG. 1 in the fourth configuration.

The broken lines in the drawings depict environment, or portions, of the set of modeling blocks that form no part of the claimed design. The appearance of any portion of the article between the break lines forms no part of the claimed design. The surface shading in FIGS. 1-32 indicates a

surface having a different color and/or texture from an unshaded surface.

1 Claim, 18 Drawing Sheets
